UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Original application filed May 24, 1924, Serial No. 715,537. Divided and this application filed January 17, 1925. Serial No. 3,009.

To all whom it may concern:

Be it known that I, HAROLD G. WARR, a citizen of the United States, residing at Park Ridge, in the county of Cook and 5 State of Illinois, have invented certain new and useful Improvements in Rail Anchors, of which the following is a specification.

My invention relates to rail anchoring devices and has for its object the provision 10 of an improved two-piece anchor device, which is so formed as to be simple of design, efficient in its operation, rigid in construction, and which may be manufactured at low cost.

15 A more specific object of the invention is to provide an improved anchor device comprising separately formed members provided with means for engaging the edges of a rail, and with interlocking wedge portions which cooperate to effect a firm grip 20 of the members with the rail when one member of the device is driven into wedging engagement with the other, one of said members being formed so that it may be 25 conveniently made of sheet metal.

The invention consists in the new and improved constructions relating to two piece rail anchors, as will be hereinafter described and claimed for carrying out the 30 above stated objects, and such other objects as will appear from the following description of the embodiments shown in the drawing, wherein:

Fig. 1 is a view in elevation of a rail anchor, constructed in accordance with my invention, showing the parts thereof in interlocked engagement and in their normal operative position on a rail base.

Fig. 2 is a plan view of the construction 40 shown in Fig. 1.

Fig. 3 is a view in perspective of one of the parts of the anchor showing the preferred construction when the member is formed from a sheet metal blank.

45 Fig. 4 is a view in perspective of the other member of the anchor, which member interlocks with the member shown in Fig. 3, when the anchor is applied to a rail, and

50 Fig. 5 is a view on a reduced scale, showing the outline of the blank from which the sheet metal member shown in Fig. 3 is formed.

Referring to the drawing, 10 designates the base portion of a railroad rail, and 11

one of the cross ties on which the rail is 55 supported.

My improved rail anchor device consists preferably of two jaw members 12 and 13, which have a wedging interlocking engagement with each other at one side of the 60 rail base 10. The member 12 is formed at one end with spaced vertically disposed jaw portions 14 and 15. These jaw portions are formed by bending the margins 16 and 17 of the blank downwardly at right angles 65 to the flat body portion 18. This construction makes it practicable to use a relatively light sheet of metal, since the downwardly bent margins 16 and 17 of the blank provide rigidifying flanges 19 and 20 of the 70 finished anchor member. The flange 20 is provided with an extension 21 which provides a tie abutment of suitable area for bearing against one of the vertical faces of the tie 11. The end 22 of the blank is 75 preferably sheared on a diagonal line, and is bent on a line parallel to the diagonal edge to provide an upstanding flange 23, which normally projects beyond the edge 80 of the rail base and extends at an angle thereto, so as to provide a wedge surface 24 which cooperates with the jaw member 13, to effect a firm grip of the anchor on opposite edges of the rail base, when the member 13 is driven to its normal operative position. The jaw portions 14 and 15 are formed with recesses 14a—15a of a configuration corresponding to the edge of the rail base, and are adapted to be driven into 85 tight wedging engagement with the upper 90 and lower surfaces of the rail base. In order to form the lower surface of the rail base receiving recesses on a plane with the top of the body portion of the member 12, the flanges 19 and 20 are formed with transverse recesses 26—26 near the end of the horizontal portion of the body.

The member 13 is preferably, though not necessarily, made of cast metal, and is formed with a jaw 27 for engaging the 100 upper inclined surface of the rail base, a wedge 28 so disposed as to extend between the edge of the rail base and the wedge flange 23 of the member 12, and with a lower flange 29. The flange 29 is preferably tapered to correspond to the taper of the wedge surface 24 of the member 12 and bears against the extremity of the downturned flange 19,

so as to prevent any substantial downward rocking of the member 13 when it is driven to its rail gripping position. In applying the anchor to a rail, the jaws of the member 12 are first hooked over one edge of the rail base, and the member positioned adjacent the cross tie 11, so that the tie abutting flange 21 will bear against one of the vertical faces of the cross tie. The member 13 is then positioned on the other side of the rail base with the wedge portion 28 disposed between the edge of the rail base and the flange 23. The member 13 may then be driven longitudinally of the rail, in a direction toward the tie, to force the wedge 28 into the space between the angularly disposed flange 23 and the adjacent edge of the rail base, thereby exerting a firm wedging grip between the flange 23 and the adjacent edge of the rail, and also effecting a firm grip of the jaws 14 and 15 on the opposite edge of the rail.

While I have illustrated my invention in one specific embodiment, it will be obvious that modifications might be made without departure from the spirit of the invention. It will therefore be understood that I contemplate all variations in structure coming within the scope of the appended claims.

30 This application is a division of my co-pending application, Serial 715,537, filed May 24, 1924.

I claim:

1. A rail anchor comprising two interlocking members, one of which is made of sheet metal and formed at one end with means for engaging one edge of a rail base and provided at the other end with a flange normally extending at an acute angle to the longitudinal axis of the rail, and spaced away from the adjacent edge of the rail base; the other of said members being provided with means having a wedging engagement between said flange and the adjacent edge of the rail base.

2. A rail anchor comprising two interlocking members, one of which is made of sheet metal, and formed at one end, with means for engaging one edge of a rail base and provided at the other end with an upstanding flange, normally extending at an acute angle to the longitudinal axis of the rail and spaced away from the adjacent edge of the rail base; the other of said members being provided with means having a wedging engagement between said flange and the adjacent edge of the rail base.

3. A rail anchor comprising two interlocking members, one of which is made of sheet metal and formed at one end with means for engaging one edge of a rail base and provided at the other end with a flange normally extending at an acute angle to the longitudinal axis of the rail and spaced away from the adjacent edge of the rail

base; the other of said members being provided with a jaw for bearing against the top surface of the rail base and having a wedging engagement between said flange and the adjacent edge of the rail base.

4. A rail anchor comprising two interlocking members, one of which is made of sheet metal, and formed at one end with means for engaging one edge of a rail base and provided at the other end with an upstanding flange normally extending at an acute angle to the longitudinal axis of the rail and spaced apart from the adjacent edge of the rail base; the other of said members being provided with a jaw for bearing against the top surface of the rail base and having a wedging engagement between said flange and the adjacent edge of the rail base.

5. A rail anchor comprising two interlocking members, one of which is made of sheet metal and formed at one end with spaced jaws for engaging one edge of a rail base and provided at the other end with a flange, normally extending at an acute angle to the longitudinal axis of the rail and spaced away from the adjacent edge of the rail base; the other of said members being provided with means having a wedging engagement between said flange and the adjacent edge of the rail base.

6. A rail anchor comprising two interlocking members, one of which is made of sheet metal and formed at one end with means for engaging one edge of a rail base, and provided at the other end with a flange which normally extends at an acute angle to the longitudinal axis of the rail, and provided at a point below the rail with a bearing surface; the other of said members being provided with means adapted to be driven into a wedging position between said flange and the adjacent edge of the rail base, and provided with means engaging said bearing surface.

7. A rail anchor comprising two interlocking members, one of which is made of sheet metal and formed at one end with means for engaging one edge of a rail base, and at the other end with a flange which normally extends at an acute angle to the longitudinal axis of the rail and spaced away from the adjacent edge of the rail base, and means providing a bearing surface below the rail; the other of said members being provided with means adapted to be driven into a wedging position between said flange and the adjacent edge of the rail, and provided with an angularly disposed flange for engaging said bearing surface.

8. A rail anchor comprising two interlocking members, one of which is made of sheet metal and formed at one end with means for engaging one edge of the rail base, and at the other end with a flange normally extending at an acute angle to the longitudinal

- axis of the rail, and means providing a bearing surface below the rail base; the other of said members being provided with means adapted to be driven into a wedging position between said flange and the adjacent edge of the rail, and provided with a flange having an edge which extends at an acute angle to the longitudinal axis of the rail adapted to engage said bearing surface.
10. 9. A rail anchor comprising two interlocking members, one of which is made of sheet metal and formed at one end with means for engaging one edge of the rail base and provided at the other end with a flange which normally extends at an acute angle to the longitudinal axis of the rail, and spaced away from the adjacent edge of the rail base; the other of said members being provided with a jaw for bearing against the top surface of the rail base and provided with a horizontally disposed flange having a diagonal edge adapted to bear against said bearing surface.
10. A rail anchor comprising two interlocking members, one of which is made of sheet metal and formed at one end with means for engaging one edge of a rail base, at the other end with a flange extending at an acute angle to the longitudinal axis of the rail, and formed intermediate said flange and said means with downwardly bent marginal portions; the other of said members being formed with a jaw adapted to engage the upper surface of the rail base and to have a wedging engagement between said flange and the adjacent edge of the rail base and provided with an angularly disposed flange adapted to bear against the downwardly bent flange of the first mentioned member.
11. A rail anchor comprising two interlocking members, one of which is made of sheet metal and formed at one end with spaced jaws for engaging one edge of a rail base and at the other end with an upstanding flange which normally stands a short distance away from the other edge of the rail base and extends at an acute angle to the longitudinal axis of the rail, and provided intermediate said jaw portions and said flange, with marginal rigidifying flanges, one of which is provided with an extension adapted to bear against one of the vertical faces of a cross tie; the other of said members being formed with means for engaging the upper surface of the rail base, provided with a wedge-shaped portion adapted to be driven between the edge of the rail base and the upstanding flange on said other member, and with a flange having a wedging surface adapted to bear against the extremity of one of said rigidifying flanges when said members are interlocked in their rail gripping position.
12. A rail anchor comprising two interlocking members, one of which is made of sheet metal and formed at one end with spaced jaws for engaging one edge of the rail base, and at the other end with an upstanding flange, which extends at an acute angle to the longitudinal axis of the rail, and provided intermediate said flange and jaw portions, with a rigidifying flange; the other of said members being formed with means for engaging the upper surface of the rail base, provided with a wedge shaped portion adapted to be driven between the edge of the rail base and the upstanding flange portion on said other member, and with a flange having a diagonal edge adapted to bear against the extremity of said rigidifying flange.

HAROLD G. WARR.
